UNITED STATES PATENT OFFICE.

GUY BENNETT WAITE, OF NEW YORK, N. Y.

CONCRETE-SLAB FLOOR CONSTRUCTION.

1,163,187.

Specification of Letters Patent. Patented Dec. 7, 1915.

Application filed July 29, 1911. Serial No. 641,237.

To all whom it may concern:

Be it known that I, GUY B. WAITE, a citizen of the United States, and resident of the borough of Queens, county of Queens, city of New York and State of New York, have invented certain new and useful Improvements in Concrete-Slab Floor Construction, of which the following is a specification.

10 This invention relates to concrete slab floor construction and is adapted particularly for use where it is desired to give a flat ceiling line.

One of the main objects of the invention 15 is to provide a construction wherein the amount of reinforced concrete used will be reduced to a minimum without sacrificing any of the strength of the structure.

Another object of the invention is to provide 20 a construction which may be erected with the use of very slight centering under the floor slabs between the floor girders or beams, thereby materially decreasing the cost of construction.

25 Another object of the invention is to provide a construction wherein the floor or ceiling slabs may be made in a suitable plant or factory and then may be readily and cheaply placed in position in the building.

30 Other important objects and advantages of the invention will appear hereinafter.

In the drawings Figure 1 is a plan view 35 of a portion of a flooring construction showing the columns and girders and the floor construction; Fig. 2 a plan view of one of the floor slabs; Fig. 3 a perspective view of a floor slab provided with one of the space-forming caps; Fig. 4 a transverse sectional view of the slab and cap as shown in Fig.

40 Fig. 1; Fig. 5 a transverse vertical sectional view of a portion of the complete floor; Fig. 6 a detail plan view of a portion of a floor showing the caps elongated and extending the entire distance between the reinforced

45 girders and showing the reinforcing rods running in only one direction between the girders; Fig. 7 a detail vertical sectional view showing a modified form of the means for locking the floor slabs to the concrete;

50 Fig. 8 a detail vertical sectional view showing another form of means for locking the floor slabs to the concrete and alining the lower surfaces of the slabs; Fig. 9 a vertical sectional view showing the metal caps temporarily supporting the floor slabs; Fig.

55 10 is a transverse sectional view of the con-

struction shown in Fig. 9; and Fig. 11 is a detail perspective view of one of the slabs shown in Figs. 9 and 10.

The invention consists generally of flat 60 slabs formed of cement, concrete or other suitable material, laid on temporary supports at the ceiling line of a proposed reinforced concrete floor. On the tops of these slabs hollow caps are laid in rows leaving 65 passageways between the caps for the insertion of the reinforcing rods and the concrete. The slabs are provided with various means for engaging each other where they meet and also are formed with ridges for 70 holding the caps in place, said ridges also serving the purpose of strengthening the slabs.

The caps may be made of any suitable material, but are preferably formed of sheet 75 iron or similar material shaped to fit down over the ridges of the slabs, all of which will be fully hereinafter described.

Referring to the various parts by numerals 1 designates the supporting columns 80 which may be of any suitable construction; and 1^a the floor beams supported by the columns and adapted to be inclosed in concrete. The floor slabs 2 are supported on any suitable form of temporary centering 85 arranged between the floor girders. Around the girders are formed boxes, in the usual manner, to receive the concrete, and the edges of the adjoining floor slabs extend into said boxes, as indicated in Fig. 5 so that 90 their edges are embedded in the concrete surrounding said girders. Each floor slab is formed with upstanding ridges 3 formed a suitable distance inwardly from the edges of the said slab so that there is a flat surface 95 4 between said ridges and the adjoining edges of the slab. These ridges are shown in the drawings as forming a rectangular upstanding flange or ridge around the four sides of the rectangular slabs. It is manifest, however, that said flanges may be arranged in any desired form, but it is preferred to form them as shown in the drawings. The meeting edges of the floor slabs are recessed to form the interlocking edges 5 so that when said flanges are interlocked the under surfaces of the slabs are alined. By 100 this means the ceiling formed by the under surface of the slabs will be comparatively smooth, and in the cheaper grade of buildings need not be plastered or finished. By 105 providing the slabs with the interlocking

flanges as described the said slabs may be more readily maintained in proper alignment with a comparatively small amount of temporary centering or supports. Other means for keeping the meeting edges and the under surfaces of the blocks alined may be employed. A modified means for this purpose is shown in Fig. 8.

10 Fitting over the flanges of each floor slab is a cap 6 of any suitable material and of the desired depth. The open side of the cap receives the flanges of the slab so that said flanges are inclosed within the cap, as clearly indicated in Figs. 4 and 5 of the drawings.

15 These caps are shown as rectangular in order to adapt them to fit the rectangular flanges or ridges on the floor slabs, but, of course, they may be shaped as desired, it being only necessary that they shall receive within them the flanges on the slabs. The vertical sides of these caps may be of any desired height, depending upon the thickness of concrete it is desired to place between said caps, as will be hereinafter described.

20 25 When the floor and the caps are arranged as shown in Fig. 1 of the drawings, passageways or channels 7 are formed between them, said channels running at right angles to each other and crossing each other as shown. In these channels are arranged the reinforcing bars 8, said bars running in both directions and crossing each other as shown clearly in Fig. 1. Each slab is formed with the metallic loops 9 which extend upwardly 30 from the surfaces 4, at opposite sides of the slab and lie in the channels 7 and become embedded in the cement of the finished floor, thereby locking the slabs to the floor structure. The wire forming these loops is preferably carried through the cement slabs, as shown clearly in Fig. 4 of the drawings and thereby strengthens the slab. It is manifest that any suitable means may be employed for locking the slabs to the concrete, one 35 modified arrangement being shown in Fig. 45 7. The loops 9 not only form a secure anchoring means but serve as handles by means of which the blocks may be readily manipulated and placed in proper positions in the 50 floor structure.

When the caps are formed of sheet metal they are preferably provided with grooves 10 in their tops and vertical sides for the purpose of stiffening and strengthening them. It is obvious, however, that if they are formed of metal of sufficient thickness, these grooves may be dispensed with.

55 In Fig. 6 caps 6^a are shown which extend the entire distance between the floor girders. 60 When caps of this form are used channels 7^a are formed between them and in said channels are arranged the reinforcing rods 8^a. It is to be noted that the channels 7^a and rods 8^a run in only one direction. This 65 makes a very simple and convenient con-

struction where the span between the floor girders is short. If however, spaces between permanent supports are short then no reinforcing rods 8^a will be necessary.

In Fig. 7 the floor slabs are provided along their edges with the upstanding flanges 11 which are under-cut at 12 to provide means for locking the slabs to the concrete. It is manifest that when the concrete hardens the said slabs will be locked thereto by reason of the under-cut and dove-tail parts 12. It is manifest that these upstanding flanges may be formed in many ways to secure the interlocking of the slabs to the concrete.

80 In Fig. 8 the abutting edges of the floor slabs are brought to a comparatively sharp edge, as at 14, by beveling the edges of the blocks, so that they may be readily brought together and their lower surfaces alined. Each slab is provided with an outwardly and upwardly extending clip 15 which bridges the joint between the slabs and rests on the upper surface of the adjoining slab so that the slabs support each other in proper alinement. The ends of these clips are turned up, as at 16, to form means for anchoring the slabs in the concrete.

85 It is manifest from the foregoing that the weight of the floor is very materially reduced by reason of the use of the caps 6. These caps form air spaces, and consequently materially lighten the structure. It is manifest that the vertical sides of these caps may be as deep as desired in order to 90 adapt the invention for use with floors of various carrying capacities. In short spaces the metal caps may be used to support the concrete slabs forming the ceiling and also carry the concrete floor without other supports. By deepening the sides of the caps the reinforced concrete portions 13 between the caps will be deeper and consequently capable of supporting a greater weight. The concrete portions 14 over the caps may be 100 as thick as desired, but need be of very slight thickness, as is manifest. The metal caps 6 when set in the concrete become very rigid, and the entire structure constitutes a very rigid but exceedingly light floor structure.

105 It is manifest that a very material part of the concrete is saved. It is also manifest that by the use of this system of construction the concrete and reinforcing rods are arranged at the proper points to give ample 110 rigidity and strength to the structure. It is also clear that the concrete is eliminated from those places where it is performing no useful purpose, that is to say from those 115 points where it does not add strength to the structure. It is manifest that at those points it is desirable to lighten the floor construction to the greatest possible extent. By the use of the sheet metal caps the cement or concrete is placed precisely where it is most 120 125 130

needed and where it performs its work most efficiently.

In Fig. 9 the caps 17 bridge the space between, and rest on, the supports. The floor slabs 18 are provided with wires 19 which pass through the slabs horizontally, their free ends extending upwardly to adapt them to be twisted about the caps and to serve as ties by which the slabs are temporarily secured to the caps. The slabs are formed with longitudinally extending ribs 20 which fit within the caps and brace the lower edges of the side walls thereof and prevent them being crushed inwardly by the concrete. The tie wires 19 also serve as means for interlocking the slabs with the concrete.

The cement floor slabs and the metal caps may be made up at a suitable plant or factory and may be easily transported to the building to be erected. It is also manifest that as these caps and slabs are extremely simple in construction they may be very readily and cheaply manufactured. By reason of the simplicity of the construction of the caps and slabs and their simple arrangement in the completed structure, they may be erected by comparatively unskilled, and consequently cheap, labor.

It is manifest that the under sides of the slabs may be shaped as desired in the factory so that the finished ceiling will have the desired appearance.

Another important advantage is the lightness of the construction wherein long spans, and consequent deep floors, are of practically the same weight as short spans.

Having thus fully described my invention, what I claim as new and desire to secure by Letters Patent, is:

1. A floor construction comprising supports, a series of rectangular cement floor slabs arranged side by side and extending over the space between said supports, each of said slabs being formed with an upstanding flange a suitable distance inwardly from its edges, a rectangular sheet metal cap adapted to fit down over each of said flanges on each of said slabs, reinforcing rods arranged between said caps, concrete embedding the caps and the reinforcing rods, means carried by the slabs for interlocking the abutting edges of the slabs to maintain the under surfaces of the slabs in horizontal alinement, and means carried by each of said slabs and extending up into the concrete to anchor said slabs to said concrete.

2. A floor construction comprising supports, a series of cement floor slabs arranged side by side and extending over the space between said supports, each of said slabs being formed with an upstanding flange a suitable distance inwardly from its edges, a sheet metal cap adapted to fit down over the flanges of each of said slabs, means carried by the slabs for interlocking the abutting

edges of the slabs to maintain the under surfaces of the slabs in horizontal alinement and means carried by each of said slabs and extending up into the concrete to anchor said slabs.

3. A floor construction comprising supports, a series of rectangular floor slabs extending over the space between said supports, a sheet metal cap arranged to fit on each slab, said cap being formed with strengthening ribs, means on the slabs for centering said caps on the floor slabs, and means carried by the slabs for interlocking the abutting edges of the slabs to maintain the under surfaces thereof in horizontal alinement.

4. A floor construction comprising supports, a series of floor slabs bridging the space between said supports, a sheet metal cap corresponding in shape to the plan view of the slabs, one cap resting on each of said slabs, means on each slab adapted to be engaged by the lower edges of each cap to prevent the side walls of said caps being forced inwardly, upwardly extending long flat loops carried by each slab near opposite edges, and a mass of concrete over the caps and the slabs and interlocking with the upwardly extending loops on the slabs.

5. A floor construction comprising supports, a series of rectangular floor slabs bridging the space between said supports, a rectangular sheet metal cap on each floor slab, an upstanding flange parallel with each edge of the slab and adapted to fit within the rectangular cap, said flanges preventing the sides of the caps being forced inwardly, an upstanding loop near opposite edges of the slab and on the upper side thereof, and a mass of concrete over the caps and slabs and interlocked with the upstanding loops.

6. A floor construction comprising supports, a series of slabs or plates bridging the space between said supports, a sheet metal cap mounted on and supported by each of said plates, said caps being smaller in plan view than said plates, means on each plate or slab adapted to be engaged by the lower edges of the cap supported by said plate to hold the side walls of said cap in position, upwardly extending locking means carried by each slab or plate said means being outside of the cap, and a mass of concrete over the caps and the slabs and embedding the locking means on the slabs and locking the slabs to the concrete.

7. A floor construction comprising supports, a series of rectangular floor slabs or plates bridging the space between said supports, a series of rectangular sheet metal caps on said floor slabs, upstanding flanges on said slabs parallel with opposite edges thereof and fitting within the rectangular caps, said flanges preventing the sides of the caps from being forced inwardly an up-

standing locking device carried by each slab outside of the caps, and a mass of concrete over the caps and slabs and embedding the locking device to hold the slab to the concrete.

8. A floor construction comprising supports, a series of rectangular floor slabs bridging the space between said supports, a rectangular sheet metal cap on each floor slab, upstanding flanges parallel with opposite edges of each slab and adapted to fit within the rectangular cap, said flanges pre-

venting the sides of the caps being forced inwardly, an upstanding locking device near opposite edges of the slab and on the upper side thereof, and a mass of concrete over the caps and slabs and interlocked with the locking devices.

In testimony whereof I hereunto affix my signature in the presence of two witnesses. 20
